UNITED STATES PATENT OFFICE.

JOHN G. MCPHERSON, OF MATTOON, ILLINOIS.

SAND-DRIER.

SPECIFICATION forming part of Letters Patent No. 276,445, dated April 24, 1883.

Application filed December 20, 1882. (No model.)

To all whom it may concern:

Be it known that I, JOHN G. MCPHERSON, of Mattoon, in the county of Coles and State of Illinois, have invented a new and Improved 5 Sand-Drier, of which the following is a full, clear, and exact description.

This invention consists of a sand-drier, more especially adapted for drying the sand used on locomotives, the drier being formed with a 10 central fire-chamber, with suitable pipes or flues leading from the top thereof, and a surrounding wall or jacket forming a sand-receiving chamber around and above the fire-chamber, the drier being adapted to receive the 15 sand to be dried at the top and to discharge it at the bottom.

The invention also consists of the particular construction, combination, and arrangement of the parts of the drier, all as herein- 20 after described and claimed.

Reference is to be had to the accompanying drawings, forming part of this specification, in which similar letters of reference indicate corresponding parts in both the figures.

25 Figure 1 is a central sectional elevation of my invention, and Fig. 2 is a sectional plan view taken on the line $x x$ of Fig. 1.

A represents a fire-chamber. B B represent a series of circularly-arranged pipes or flues, 30 and B' a central flue. These flues lead from the chamber A up to the chamber C, formed by the dome-shaped cover D, placed over the top of the flues, as shown in Fig. 1; and E represents the outer wall, which surrounds the 35 fire-chamber and the said flues, and forms the space F around the fire-chamber and the space F' above the fire-chamber, (around and between the flues,) which spaces form the drying-chamber for the sand. In the center of the dome-shaped cover D is formed the opening d, through which the products of combustion from the fire-chamber pass. Below the fire-chamber is formed the ash-pit G, which receives the ashes from the fire-chamber. The 40 top of the surrounding wall E is provided with the hopper H, which facilitates the shoveling of the sand to be dried into the drying-chambers. At the bottom of the space F are formed the outlet-passages f f for the sand after it has 45 become thoroughly dried. While the sand is

being dried these outlet-passages are closed by the sliding plates b b, as clearly indicated in the drawings.

J represents the opening through which the fuel is placed in the fire-chamber, which opening is closed by the door K.

The drier is by preference made circular in form and of cast-iron.

The fire-chamber is cast as a separate part, with the door-frame J', the conical top L, and the circular series of short pipe-seats a a, and the central pipe-seat, a', at the apex of the cone.

The pipes B and B' are cast separate, and have the flanges e formed at their lower ends to adapt them to be set upon the upper ends 65 of the pipe-seats a and a'. The upper ends of the pipes B are held in place by the circular plate N, which is formed with as many openings n as there are pipes B, and with a central opening, n', for the passage of the upper 70 end of the central pipe, B', and this plate N is formed upon its under side with the circular flanges m to retain the upper ends of the pipes, and the outer edge of the plate is formed with the upwardly-projecting circumferential 75 flange o for retaining the cover D, which fits within the said flange o, as shown in Fig. 1.

The ash-box G is a separate casting, and it supports the whole structure upon the annular plate N', placed thereon, which plate is 80 larger than the ash-box, and is formed with the discharge-openings f f, above mentioned, and is formed upon its under side with the ribs d' d', which are undercut, and form the ways in which the plates b b, which open and close the 85 discharge openings f, slide. Upon this annular plate N', inside of the fire-chamber, are placed the grate-bars L', which are held in place by the rib l, and the outer edge of the plate is formed with the upwardly-projecting 90 flange l, which holds the outer wall, E, in place upon the plate, as shown in Fig. 1. The outer wall, E, is by preference formed of the cast sections h h, which are provided at their upper edges with the flanges i i, which form seats 95 for the sections above to rest in, and for the hopper H at the top of the wall.

The central pipe or flue, B', passes up through the plate N, as shown in Fig. 1, so that the expansion of this pipe, when heated, will not 100

lift the said plate off from the ends of the circular series of pipes B, and this plate N is formed with the small holes f' f' for the escape of the moisture which rises from the sand in the drying-chamber.

5 In use the sand to be dried is shoveled into the hopper H, from whence it falls into and fills the space F, surrounding the fire-chamber, and also the space F', above the fire-chamber, 10 filling it around the pipes and upon the cone L. After the sand has become thoroughly dry from the heat from the fire-chamber the slides b b are to be withdrawn for opening the passages f, which permits the sand to flow out of 15 the chambers, the cone L causing the sand to be discharged from the chamber F' into the space F, and from thence out through the openings f.

Having thus fully described my invention, 20 what I claim as new, and desire to secure by Letters Patent, is—

1. In a sand-drier, the combination, with the fire-chamber A, having the conical top L, the pipes B B', and the plate N, provided with the 25 apertures n n', of the cover D, having central

opening, d, and the wall E, surrounding the said chamber and pipes, and provided with the hopper H, substantially as herein shown and described, and for the purpose set forth.

2. In a sand-drier, the combination, with the 30 fire-chamber A, having a conical top, the pipes B B', the plate N, having apertures n n', the cover D, and the ash-box G, of the ring N', of larger diameter than the ash-box, and provided with the discharge-openings f, the ways or 35 ribs d', and the upwardly-projecting flange l', the sliding plates b, and the wall E, provided with the hopper H, substantially as herein shown and described.

3. In a sand-drier, the combination, with the 40 fire-box A, having conical top L, of the pipes B B', the plate N, provided with the apertures n n' to receive the said pipes, and the vent-apertures f', substantially as herein shown and described.

JOHN G. MCPHERSON.
